UNITED STATES PATENT OFFICE.

JOHN WILLIAM HESS, OF KITCHENER, ONTARIO, CANADA.

COLLAR CRIMPING AND TURNING MACHINE.

Application filed May 5, 1921. Serial No. 467,120.

To all whom it may concern:

Be it known that I, JOHN W. HESS, of the city of Kitchener, in the county of Waterloo, Province of Ontario, Canada, a subject of the King of Great Britain, have invented certain new and useful Improvements in Collar Crimping and Turning Machines, of which the following is a specification.

This invention relates to machines for folding over the edges of the pieces of material from which collars used as wearing apparel are formed. In such machines it is usual to employ a thin flat form over which slideable folder plates fold the edges of material operated on, and my object is, among other things, to devise improved means for heating the folders and for slidably supporting the same, and to provide improved means for actuating the folder plates, to provide efficient means for applying pressure to the infolded edges of the material.

I attain my objects by means of the constructions hereinafter described and illustrated in the accompanying drawings, in which—

Fig. 1 is a plan view of a machine constructed in accordance with my invention;

Fig. 2 an end elevation of the same, partly in section;

Fig. 3 a similar view to fig. 2 with the folder plates in advanced position and co-acting with the former;

Fig. 4 a plan view of one of the pressure arms;

Fig. 5 a side elevation of the same; and

Fig. 6 an enlarged cross section of one of the former plates.

In the drawings like numerals of reference indicate corresponding parts in the different figures.

1 represents a portion of the frame of the machine in which is supported the bed 2.

3 are double arms fulcrumed at one side of the bed and carrying the two halves of the form 4 about which the edges of the material operated on are folded. The form, it will be noted, is formed in halves with skived overlapping edges so that the parts of the forms may be slid endwise over one another.

Each half of the form, it will be noted, is connected to one of the double arms and these arms are slidable lengthwise of the bed on the shaft 5 journalled on the frame. When the machine is in operation these arms are suitably rocked to raise and lower the forms and at the proper time are slid

lengthwise on the shaft, but with these features of construction the present invention is not concerned, and apparatus for this purpose is not shown or described.

The form 4 is adapted to rest on the center part of the bed and with it co-operates four folder plates 6 constructed as hereinafter described. These folder plates are adapted to be moved diagonally inwards towards the center of the bed and therefore to close about the form 4. The plates rest on two bars 7 which extend lengthwise of the bed, their upper surfaces being slightly above the level of the portion of the bed 70 against which the form 4 rests when in its lowered position.

The preferred arrangement of these bars is to form a projecting rib 8 at each edge of the bar, which is received in grooves 75 formed in the sides of a recess 9 extending transversely of the bed. In each recess is inserted a flat electrical heating element, preferably in close contact with the under side of the bar. The bars are made of a material of high heat conductivity and preferably of high specific heat, such, for example, as copper. The folder plates 6, which slide on this bar, are thus heated by contact therewith. These folder plates also 85 rest on washers 10, preferably of antifriction metal, which surround the pins of rollers 11 which form projections extending into diagonal slots 12 formed in the plates 6. Two rollers 11 and two slots are, of course, necessary for each plate and these slots may be suitably arranged to give any desired direction of movement of the folding plates towards one another.

The plates are actuated by two heads 13 95 which are slidable to and from the form. Preferably these heads are supported on rollers 14 running on suitable tracks on the frame of the machine. Links 15 are pivotally connected with these heads and with the plate 6, two such links being employed for each plate. Therefore, as the heads are reciprocated to and from the form, a suitable movement will be given to the plates. As the plates not only move inwardly 105 towards one another, but as will herein-after appear, require to be slightly tipped to produce a pressure on the folded edges of the material, the links are given in effect a universal joint connection both with the heads and with the plates. While any suitable construction may be employed, I show

ball-headed studs 16 connected to the plates and to the heads, while the links are provided with divided sockets 17 suitably secured about the heads of the studs.

- 5 The heads 13 are actuated by means of two slides 18 vertically movable in suitable guides at opposite ends of the machine. In each slide is formed a diagonal slot 19 into which project projections 20, preferably 10 formed as rollers. It is evident that by reciprocating the slides that the heads may be moved as desired. These slots may be given any suitable shape to give the heads a uniform movement or a varying movement as 15 may be required, and the slots are so proportioned that when the slides are really at their lower limit of movement the ends of the slots will engage the projections 20 and thus tip the heads slightly on the rollers 14 as fulcrums, these rollers being adjacent the outer sides of the heads. This tipping movement is imparted to the plates 6 by the following means. The plates, it will be noted, rest on the bars 7 slightly above the level of the bed 20 25 and are therefore easily tilted by pressure applied near their inner sides when they are closed about the form 4. This pressure is applied by means of arms 21, two being preferably employed for each of the folding plates. These arms are provided with slotted lugs 22 by means of which they are bolted to the heads, the slots providing means for adjusting to a limited extent the position of these arms. These arms are 30 35 provided at their inner ends with means for engaging the upper surface of the folding plates. The engaging means are preferably adjustable. For this purpose I provide a screw 23 threaded through the inner end of each arm. The upper end of each screw is slotted for engagement with a screw driver, whereby it may be adjusted in the end of the arm. The lower end of the screw is formed as a ball 24 and a divided shoe 25 40 45 is secured in position on the ball so as to have a rocking movement thereon. A second shoe is preferably similarly connected to the side of the arm to steady the rear part of the plate and limit the tilting of the plate. It is not necessary, however, to employ this second shoe except in the case of the outer 50 55 of the arms 21 as will be seen on reference to Fig. 1.

When the folder plates are moved to their inner positions they fold the edges of the strip of material over the form as indicated particularly in Fig. 3, and the shoes on the inner ends of the arms 21 then rest on the portions of the plates which project beyond the supporting bars 7, hence the downward pressure of the arms due to the heads being tilted as hereinbefore described will impart a downward pressure to the inward edges of the folding plates and cause them to press the inwardly folded edges of the material 60 65

tightly down against the upper surface of the form. The folder plates, being held as hereinbefore described, the folded-in portions of the material tend to retain their folded in position after the folder plates are 70 retracted. After the folder plates are retracted, the form is lifted, contracted longitudinally and the folded material is then easily removed therefrom.

In the preferred construction each folder plate is formed of two thin plates 26 and 27 suitably secured together by means of rivets or screws. The under plate 27 preferably does not extend at the inner side to the inner edge of the plate 26, so that the latter projects. A separate member 28 formed of a piece of thin sheet steel is secured beneath the extended portion of the upper plate 26 and extends beyond the same. The collar-engaging part of each form which is 80 85 most subject to wear is thus easily renewed or changed at any time.

It will be noted that certain of the folder plates have thin projecting portions 29 adapted to fit into corresponding recesses 90 formed in the opposed plates. This arrangement is intended to give substantial continuity to the folder plates, which thus operate round the entire outer periphery of the form. This arrangement, however, is 95 already known in the art. The present invention is concerned only with the parts already described and no means are therefore shown for operating the slides 18 and arms 3, such arrangements being already known 100 in the art.

What I claim as my invention is:—

1. In a collar crimping machine, the combination of a form; slideable folder plates adapted to co-operate with said form; bars 105 of copper over which said plates slide having their upper surfaces raised above the bed of the machine; and electric heating elements close beneath said bars.

2. In a collar crimping machine, the combination of a form; slideable folder plates of steel adapted to co-operate with said form; bars of copper over which said plates slide having their upper surfaces raised above the upper surface of the bed of the 115 machine; and washers on which the rear parts of the plates normally rest out of contact with the bed of the machine.

3. In a collar crimping machine provided with a bed, the combination of a form; 120 two pairs of slideable folder plates adapted to co-operate with said form, each having a pair of guiding slots formed therein; projections on the bed of the machine entering said slots; two heads slideable on the bed of the machine; and pairs of pivoted links connecting the heads and each of the folder plates.

4. In a collar crimping machine provided with a bed, the combination of a form; 125

- two pairs of slidable folder plates adapted to co-operate with said form, each having a pair of guiding slots formed therein; projections on the bed of the machine entering 5 said slots; two heads slidable on the bed of the machine and vertically rockable; pairs of links pivotally connected to the heads and each of the folder plates to swing horizontally and vertically; and presser arms 10 secured to said heads, extending over the folder plates and adapted to contact with their upper surfaces towards their operative edges.
5. In a collar crimping machine, the combination of a bed; a form; bars projecting slightly above the bed; slidable folder plates supported on said bars and having guiding slots formed therein; projections on the bed 15 of the machine entering said slots; washers round said projections on which the plates normally rest; two heads slidable on the bed 20 of the machine; and pairs of pivoted links connecting the heads and each of the folder plates.
- 25 6. In a collar crimping machine, the combination of a bed; a form; bars projecting slightly above the bed; slidable folder plates supported on said bars and having guiding slots formed therein; projections on the bed
- of the machine entering said slots; washers 30 round said projections on which the plates normally rest; two heads slidable on the bed of the machine and vertically rockable; pairs of links pivotally connected to the heads and each of the folder plates to swing 35 horizontally and vertically; and presser arms secured to said heads, extending over the folder plates and adapted to contact with their upper surfaces towards their operative edges. 40
7. In a collar crimping machine, the combination of a bed; a form; bars projecting slightly above the bed; slidable folder plates supported on said bars and having guiding slots formed therein; projections on the bed 45 of the machine entering said slots; washers round said projections on which the plates normally rest; a vertically movable slide at each side of the machine, each having a pair of diagonal slots formed therein; 50 and projections on the heads entering said slots.

Signed at Kitchener, Ontario, this 27th day of April 1921.

JOHN WILLIAM HESS.
